UNITED STATES PATENT OFFICE.

BREESE RIGGS, OF CROWLEY, OREGON; SETH RIGGS EXECUTOR OF SAID
BREESE RIGGS, DECEASED.

ANIMAL-GUN.

SPECIFICATION forming part of Letters Patent No. 497,607, dated May 16, 1893.

Application filed June 16, 1892. Serial No. 437,004. (No model.)

To all whom it may concern:

Be it known that I, BREESE RIGGS, of Crowley, in the county of Polk and State of Oregon, have invented an Improved Breech-Loading Animal-Gun, of which the following is a specification.

This invention is an improved gun adapted for employment in the extermination of gophers, moles and similar animals.

10 The object of the invention is to provide a breech loading gun of this character that can be arranged where most convenient and necessary and one that will be operated by the movement of the animal as it approaches the muzzle of the same.

15 With these objects in view my invention consists in the peculiar construction of the several parts and the novel manner of combining or arranging the same all of which 20 will be fully described hereinafter and pointed out in the claims.

In the drawings forming a part of this specification Figure 1 is a side view of my improved gun. Fig. 2 is a view showing a 25 portion of the barrel and the cartridge inserted in the breech of the same and Fig. 3 is a central longitudinal section of the gun.

In the practical embodiment of my invention I employ a barrel F, of suitable length 30 and diameter, open at the breech and threaded externally at that end for engagement with a connecting sleeve or band G, said sleeve being threaded internally at each end and between such threaded ends the sleeve is 35 formed with a shallow internal recess g the purpose of which will appear farther on. The breech tube C is screwed into the rear end of the sleeve G and between the breech end of barrel and the forward end of breech tube is 40 arranged a disk g' which is seated within the recess g above referred to as clearly shown and is formed with a central aperture g² through which the needle point b of the firing pin B is adapted to pass in order to im- 45 ping against the cartridge F', located within the breech of the barrel F. The firing pin B is located within the breech tube C and near its forward end is attached a collar or nut b² against which the forward end of the spring 50 A bears. Said spring is coiled spirally around the pin and confined within the tube by means

of the cap C', said cap being perforated to permit the movement of the pin B. The rear end of the pin is provided with a knob to enable one to draw it rearward in order to set 55 the gun ready for action. When the pin is thus moved rearward the spring A is compressed between the collar or nut b² and the cap C' and the moment the pin is released the spring expands, forcing the pin forward, 60 the needle point through the central aperture of disk and exploding the cartridge. In order to retain the pin B when drawn back and also to permit the gun to be discharged by the animal approaching the muzzle of the 65 same I provide a trigger D and a tripping rod E which is connected with the trigger and extends forward beyond the muzzle in the path of the animal. The trigger D consists of a long plate perforated near one end to 70 permit the pin B to move through the same, said pin having a notch H upon its upper side which is engaged by the trigger D thus holding the pin in its set position. The trigger D is also bent at this end said bent portion 75 bearing against the cap plate as shown. The opposite end of the trigger is connected with the tripping rod E which passes through an eye f on the end of barrel and projects in the path of the animal.

80 In operation—the barrel is detached from the sleeve G, a cartridge inserted in the breech of same, and then replaced. The gun is then stapled or otherwise secured in the desired position preferably at the entrance of the hole 85 of the gopher and the firing pin drawn out and locked in such set position by means of the trigger. The animal in moving toward the muzzle of gun comes into contact with the tripping rod E which being moved lifts 90 the trigger out of engagement with the notch H and the spring A being free to act forces the pin forward, the point through the disk and discharges the cartridge. The collar or nut serves also as a guide and insures the 95 proper registering of the point with the aperture.

Having thus described my invention, what I claim is—

1. In an animal gun, the combination with 100 a sleeve having an inclined recess, of a barrel secured in the forward end of the sleeve,

a breech tube secured in the rear end, a centrally apertured, detachable disk arranged within the recess of the sleeve and a firing pin arranged in the breech tube substantially as shown and described.

5 2. In an animal gun the combination with a detachable barrel adapted to receive a cartridge in its breech, of a breech tube carrying a firing pin, a sleeve connecting the barrel and tube and a centrally apertured detachable disk arranged within the sleeve between the barrel and tube, substantially as described.

10 3. The combination with the sleeve barrel and tube of the apertured detachable disk the firing pin having a collar at its forward end and a notch about midway its length the

trigger having its upper end perforated to receive the pin and bent at said end to bear against the cap of tube and the tripping rod 20 all arranged as shown and described.

4. The combination with a sleeve having an inclined recess, the barrel open at each end, the breech tube open at each end, the detachable apertured disk arranged in the 25 recess of the sleeve, the firing pin and spring, the cap, the trigger having an aperture and a bent end portion and the tripping rod connected to the opposite end substantially as shown and described.

BREESE RIGGS.
